STAPLE PULLER AND INSULATOR REMOVER

Filed April 14, 1949

UNITED STATES PATENT OFFICE

2,577,911

STAPLE PULLER AND INSULATOR REMOVER

Richard A. E. Palmer, Alburg, Vt.

Application April 14, 1949, Serial No. 87,465

3 Claims. (Cl. 254—22)

1

This invention relates to wire fence tools in the form of tongs or pliers adapted particularly for pulling staples and nails, and removing insulators from the fence posts of electrified fences.

One of the most commonly used forms of fencing, particularly in rural areas, consists of wood fence posts to which strands of barbed or plain wire are secured by staples. In cattle raising districts such fences are frequently electrified, the charged wires being supported by insulators secured to the posts by nails. At times it is necessary to move such fences or to repair them, and it is a troublesome and time consuming operation to remove the staples and nails from the posts without breaking the wires and insulators.

The principal object of the invention is to provide a simple and highly effective tool by which such work may be done quickly and easily without damage to the wires or insulators, and which may also be used in erecting such fences and in repairing them.

Other objects and advantages of the invention will be set forth in the following description of the present preferred embodiments of the invention shown in the accompanying drawings, in which:

Fig. 1 is a side elevation of the tool showing the jaws in their closed positions, with portions of the handles broken away.

Fig. 2 is a reduced detail edge view of the tool showing one application of it to a portion of a fence post having a wire stapled to it.

Fig. 3 is a detail section taken on line 3—3 of Fig. 2 looking in the direction of the arrows and showing one stage in the operation of pulling a staple.

Fig. 4 is a view similar to Fig. 3 showing another position of the staple pulling claws when the staple is partially extracted.

Fig. 5 is a detail edge view of the tool showing its position with respect to a post when the staple has been completely removed from the post.

Fig. 6 is a detail section taken substantially on the plane of the line 6—6 of Fig. 1 looking in the direction of the arrows, and showing the rear sides of the claw portions of the jaws.

Fig. 7 is a detail edge view of the tool showing diagrammatically the manner of using the tool when an insulator is to be removed from a post.

Fig. 8 is a view on a much reduced scale showing the invention embodied in a pair of pliers adapted for pulling staples.

The tool illustrated in Fig. 1 comprises a pair of crossed levers 10 and 11 connected nearer to one of their ends by a pivot 12 to provide on one

2

side of the pivot handles 13 and 14 and on the other side a pair of jaw members 15 and 16. The handles may be relatively long when the tool is in the form of a pair of tongs and may be of any cross-sectional shape. At their points of pivotal connection and on each side thereof, the levers are widened and made flat as shown in Fig. 1, the opposed faces of the crossed portions being held in contact by the pivot 12 which may be in the form of a bolt or a rivet. The relatively short jaws 15 and 16 are substantially U-shaped in side elevation, and are opposed to each other, their free or outer ends carrying similar and coacting combined claw and fulcrum members 17 and 18 generally indicated by the numerals 17 and 18. If desired the flat portions of the levers in front of the pivot may be formed with the usual coacting wire cutting notches 19, and at the rear of the pivot with opposed toothed or serrated edges 20 to be used in gripping a wire to pull or stretch it, or for wire splicing. A hammer head 21 may be formed on the outer curved portion of the jaw 15 to be used in driving staples or nails or for similar operations.

25 In the drawing P denotes a portion of a wood fence post, W a fence wire, S a staple, I an insulator, and N a nail fastening the insulator to the post. When the tool is to be used for either pulling a staple or removing an insulator from a fence post, the combined claw and fulcrum members 17 and 18 will be made relatively long and will project from both sides of the longitudinal axis of the tool as shown in Figs. 1, 2, 5 and 7. These members which extend transversely of the levers in the direction of the axis of the pivot 12, are integrally formed with the ends of flat and widened portions 22 of the jaw members 15 and 16, their points of connection being such as to provide, on one side of the tool, relatively short claw portions 23 to be used for pulling staples or nails which may be used for fastening fence wires, and on the other side of the tool much longer claw portions 24 to be used in removing insulators, as will be understood on reference to Fig. 7. The two members 17 and 18 are of the same construction and their opposed faces contact each other in the same plane which intersects the longitudinal axis of the pivot 12 as seen in Fig. 1. 30 Their inner or rear faces have flat areas 25 as seen in Fig. 6 but said faces are formed with deep undercut portions forming concave recesses 26 in the opposed faces of the members. These recesses extend over substantially the entire area 35 of the opposed faces of the members and form

relatively sharp or V-shaped gripping edges 27 which extend longitudinally of the outer portions of the members and are adapted to contact each other when the tool is in its closed position. These edges extend substantially to the rounded extremities of the members 17 and 18 as shown in Fig. 6, and they will be effective in gripping the opposite sides of a staple, nail or the like as shown in Fig. 4. The front or outer surfaces of the members 17 and 18 are curved in a longitudinal direction, preferably as shown, from one end to the other, and are also provided with the transverse curvature shown in Figs. 1 and 4. The longitudinal curvature of the outer face of each of the short ends 23 merges into a straight or beveled area 28 although the latter also has the transverse curvature shown in Fig. 3. The inner or rear face of each of the ends 23 is also slightly beveled as at 28a to give said ends relatively sharp extremities to enable them to be pushed or hammered into a post close to the opposite sides of a staple when the latter has been driven rather deeply into the post. The rear or inner faces of the long ends 24 are also slightly beveled as shown at 29 to facilitate the engagement of said ends between the post and opposite sides of the end of the insulator I as shown in Fig. 7. It will be seen that the curved front surfaces of the members 17 and 18 form fulcrums which may rock on the post and which may be moved toward and from each other by manipulating the handles so that claw ends 23 or 24 may be positioned on opposite sides of the staple, nail, insulator or other element which is to be moved by the tool. By making the member 17 and 18 relatively long and having their end claws project from opposite sides of the levers, a long and effective rocking fulcrum is obtained to make the tool extremely effective for its intended uses.

In Fig. 8 is shown a tool in the form of a pair of pliers having the improved staple pulling feature. The crossed levers 10a and 11a are pivotally connected at 12a to provide handles and short jaws. Combined claw and fulcrum members are formed on the jaws and extend on opposite sides of the longitudinal axis of the tool, the staple pulling end claws 23a being the same as the ends 23 in the first described form. Instead of forming the insulator removing claws on the oppositely projecting ends of the members, I provide said ends with hammer sections 28a which when the tool is closed contact with each other to form a two-part cylindrical hammer head. The latter may be struck by another hammer when it is desired to drive the pointed extremities of the ends 23a into a post to get the ends behind a wire held by a deeply embedded staple. To facilitate the same operation when the combined tool shown in the first form is used, I may strike the head of the pivot 12 with a hammer. Such head or the entire pivot may be hardened, and if desired the pivot may have an enlarged striking head 30 on the side of the tool opposite the ends 23, the opposite end of the pivot being upset as shown at 31.

It is believed the manner of using the tool will be apparent from the foregoing detailed description in connection with the drawings, but it might be explained that when a staple holding a wire to a post is to be pulled, the members 17 and 18 are separated sufficiently to position the claw ends 23 behind the wire and on opposite sides of the staple with the curved fulcrum surfaces in contact with the post. At

first the pointed extremities of the ends 23 are positioned as close to the staple as possible, and the tool is then rocked by means of the grasped handles. In thus positioning the ends 23, the pivot head 30 may be struck by a hammer so that the pointed extremities of the ends 23 will dig into the post. Fig. 3 shows substantially the position of ends 23 at the beginning of the pulling operation. When the staple has started to move out of the post and the wire has moved slightly away from the post, the ends 23 may be moved downwardly on the wire and may also be brought closer together to the position shown in Fig. 4 so that the sharp edges 27 may grip the opposite sides of the staple. The tool is then further rocked on the fulcrum portions of the members to the position shown in Fig. 5 to completely remove the staple from the post. The operation of pulling the nail N to remove the insulator I is similar and will be understood upon reference to Fig. 7. The tool may be used in various other ways in erecting, repairing and removing wire fences as will be apparent to those familiar with such work.

From the foregoing, taken in connection with the accompanying drawing, it will be seen that novel and advantageous provision has been made for carrying out the objects of the invention, and while preferences have been disclosed, attention is invited to the possibility of making variations within the scope of the invention as claimed. For example, the hammer head portion 21 may be made smaller and lighter in weight and of different shape than is shown. Other changes in the shape and proportions of the parts may be made without departing from the claims.

I claim:

1. A tool for removing from fence posts wire-fastening staples and nail-fastened insulators, comprising a pair of crossed levers pivotally connected adjacent their outer ends by a pivot, their inner ends forming handles, the outer ends of said levers being U-shaped and arranged in opposed relation with their outer arms extending toward each other, and a pair of combined claw and fulcrum members fixed between their ends to said outer arms and extending crosswise thereof and in the direction of the longitudinal axis of said pivot, said members being relatively flat and narrow in width and of elongated form to extend on both sides of the longitudinal axis of the tool, the projecting end portions of said members on one side of said axis being of less length than the projecting end portions on the other side, the outer surfaces of said members being transversely curved and also longitudinally curved to provide a pair of relatively flat and narrow post-engaging fulcrums movable toward and from each other as said levers swing on their pivot, the opposed contacting faces of said members being flat and formed with opposed, deep, concave recesses which extend substantially from end-to-end of said members and form longitudinally extending V-shaped claw edges along the outer contacting portions of the members.

2. In a tool for removing from a substantially cylindrical fence post a staple which fastens a fence wire transversely of the post, the tool including a pair of crossed and pivotally connected levers having handles at their inner ends, said tool comprising a pair of combined claw and fulcrum members fixed between their ends to the outer ends of the levers in opposed relation, said members being relatively flat and narrow in width and also being of elongated form

to extend on both sides of the longitudinal axis of the tool, the outer surfaces of said members being transversely curved and also longitudinally curved to provide a pair of relatively flat and narrow post-engaging fulcrums movable toward and from each other as the levers swing on their pivotal connection, the projecting portions of said members on at least one side of said axis being outwardly beveled to provide relatively flat, sharp-pointed ends insertable between a post and a fence wire on opposite sides of a wire-fastening staple, the opposed faces of said last mentioned projecting portions of said members being formed with deep concave recesses to receive the fence wire and to provide opposed sharp, longitudinal, claw edges along the outer portions of the fulcrums to wedge between the post and the fence wire and to grip opposite sides of the staple when the handle ends of the levers are gripped.

3. In a tool of the character set forth having a pair of crossed and pivotally connected hand levers with jaw carrying portions at their outer ends, a pair of opposed and coacting, combined claw and fulcrum members on said jaw portions and extending transversely across the same and in the direction of the axis of the swinging movement of the levers, said members being relatively narrow in width and height and of elongated

form to extend on both sides of the longitudinal axis of the tool, the outer surfaces of said members being transversely curved and also longitudinally curved to provide a pair of relatively flat and narrow post-engaging fulcrums movable toward and from each other as the levers swing on their pivotal connection, the projecting portions of said members on at least one side of said longitudinal axis being formed with tapered and pointed ends, the opposed faces of said last mentioned projecting portions of said members being formed with deep concave recesses which extend over substantially the entire area of said opposed faces and provide opposed and contacting V-shaped claw edges extending longitudinally along the fulcrum portions of said members.
